DESIGN FOR A PIPE RACK COMPACT

Abraham Herst, San Francisco, Calif., assignor to
The American Import Company, San Francisco,
Calif., a corporation of California

Application August 26, 1936, Serial No. 64,577

Term of patent 7 years

To all whom it may concern:

Be it known that I, Abraham Herst, a citizen of the United States, residing in the city and county of San Francisco and State of California, have invented a new, original, and ornamental Design for Pipe Rack Compacts, of which the following is a specification, reference being had to the accompanying drawing, forming part thereof, in which:

Figure 1 is an isometric view of a pipe rack compact, showing my new design;

Figure 2 an end elevation thereof; and

Figure 3 a front elevation thereof.

I claim:

The ornamental design for a pipe rack compact, substantially as shown.

ABRAHAM HERST.
